CHARLES T. HARVEY, OF TARRYTOWN, NEW YORK.

Letters Patent No. 79,754, dated July 7, 1868.

IMPROVEMENT IN ELEVATED RAILROADS.

The Schedule referred to in these Letters Patent and making part of the same.

TO ALL WHOM IT MAY CONCERN:

Be it known that I, CHARLES T. HARVEY, of Tarrytown, in the county of Westchester, in the State of New York, have invented a new and useful Improvement in Elevated Railroads; and I do hereby declare the following to be a full, clear, and exact description thereof, which will enable those skilled in the art to make and use the same, reference being had to the accompanying drawing forming part of this specification, in which drawing—

Figure 1 is an elevation of my improvement.

Figure 2 is a plan view of the part below the sidewalk, the pavement having been removed.

Figure 3 is an elevation, in side view, of the said improvement.

Figure 4 is a plan view of the track of the elevated railroad, and of the elevated sidewalk which I combine therewith.

Figure 4 also shows, in red outlines, how the endless propelling-cable is returned to the place whence it starts.

Figure 5 is an elevation, in cross-section, of the track, with the operative and return-cable guides, the latter being shown in red.

Figure 6, sheet 2, is an elevation, showing how my elevated sidewalk is carried over an intersecting cross-street.

Figure 7 is an elevation at right angles to that shown in fig. 6, and

Figure 8 is a plan thereof.

This invention relates to elevated railroads, and consists, among other things, in a novel method of supporting or forming foundations for the columns of an elevated railroad where it goes over vaults, cellars, or other sunken places, or over sewers or other subterranean works; and it also consists in combining with the columns a sidewalk that extends to the buildings of any street where the elevated railroad is erected.

Other features of the invention will be mentioned as the description proceeds.

In building an elevated railroad upon streets, as well as private property, where there are vaults, cellars, or excavations, beneath the surface of the ground, it is desirable to avoid building piers or foundations therein, or otherwise disturbing them, and it is also desirable, in case of sewers, water and gas-pipes, and other subterranean works, to avoid interference therewith.

In order to avoid interfering with or disturbing these or other subterranean works, and yet construct an elevated railroad over the same, in a firm and secure manner, I have invented the following method of supporting, sustaining, and securing the columns.

The letter A designates a vault, appertaining to a building, whose front wall is shown at B.

The front wall of the vault is shown at C.

The letter D designates the cover of the vault, which cover constitutes also the pavement of the street-sidewalk for pedestrians.

Below the sidewalk or cover D, (or else embedded in the same, if that method of construction is preferred,) I place a strong frame, composed of beams, E, of iron, or other suitable materials, which extends across the vault, and beyond the same into the roadway, but beneath its surface, and rest upon the walls B and C.

In order to avoid interference with the curb-stone of the sidewalk, or with the gutter or roadway of the street, the beams E, after they pass the columns, are deflected downwards from a horizontal line until the gutter is passed, when they are bent back to a horizontal line. Their outer ends rest on one or more blocks or sleepers, F, embedded in the ground, proper precautions being taken to prevent displacement of the beams in any direction. Instead of deflecting the beams in this manner in order to get below the gutter and curb-stone, I can make them in two divisions, an upper and lower one, whereof the upper one shall extend to or nearly to the curb-stone, and shall rest on the lower one, which will extend thence beneath the curb-stone and gutter, and as far into the ground as is required; the two divisions being firmly bound together by the same bolts that secure the base of the columns to the beams.

In this example I have shown the beams deflected, as in fig. 3, so as to clear the bottom of the curb-stone G, and also clear the gutter of the street.

The letter I designates the base-plate of the column J, which base-plate rests upon the pavement D, and is

firmly secured thereto, and to the beams E, by means of bolts, K, and a plate or block, L, that goes under the beams, the bolts K going through both the plates I and L, and through the pavement D, in such a manner as to enclose and bind the beams and pavement between said plates. The bolts can, if desired, also go through the beams, instead of only going between and outside of them, as shown in the drawing.

The base-plate I of the column is, in this example, let into a depression or countersink made in the pavement or vault-cover D, so as to let the surface of the plate come flush with said pavement.

In order to relieve the column and structure of the railroad from unpleasant jars and noise, and to preserve the pavement from injury, I interpose a cushion, N, of wood, rubber, or other suitable elastic substance, between base-plate I and pavement D.

Where there is no objection to placing the foundation or base of a column in a vault, such foundation or base can rest on the floor of the vault, or be sunk below such floor.

The letter M designates an elevated sidewalk, which I combine with the columns of the elevated railroad. The pavement of such sidewalk is made of any suitable materials, but I prefer transparent or translucent materials, so that the transmission of light to the sidewalk below will be obstructed as little as possible.

The outer edge of the elevated sidewalk is connected to the columns, and the track of the elevated railroad, and its inner edge is connected to the walls of the buildings that line the street, and at places where there are no buildings the inner edge is supported by a wall or other structure built for that purpose.

The slabs of the pavement are, in this example, supported at their outer edges on the flange of one of the rails at the track, and at their inner edges on a rebated beam, which may be of metal, that extends along the walls of the buildings, while their sides rest on rebated beams, O, that extend from the track of the railroad to the opposite buildings, and which beams O are firmly secured to the track and to the buildings, so that they form braces for the track as well as supports for the sidewalk.

In figs. 6, 7, and 8, I have shown how I carry the elevated sidewalk, M, over a cross-street by means of a bridge, R.

J' J' are supporting-columns, placed in the cross-street, or near to its corners, and the beams O, which, in sheet 1, are seen to extend from the track to the buildings, in sheet 2 extend from the track to the said lateral columns J' J', and to the beams of frame R which connect said columns J' J' to each other, and are combined with other beams, O', to compose a frame of sufficient strength for the required purpose.

The structure is properly braced with braces P, and I place a truss-balustrade, Q, at the edge of the sidewalk, and another at the opposite side of the bridge along the track.

It will be observed that I thus form a bridge over a cross-street with the aid of only two supplementary supporting-columns, J' J', combined with the ordinary columns of the railroad, and with the track thereof.

In fig. 5, and also in fig. 4, I show in red outline a return-cable guide for the propelling-cable, arranged alongside of one of the rails.

The return-cable guide is here shown reversed from the position of the direct guide, and the cable is brought to a reverse position by suitable pulleys on a twisted guide at the ends of the course.

What I claim as new, and desire to secure by Letters Patent, is—

The combination of a supporting-column of an elevated railroad with beams E, to which it is secured, and with the pavement or cover D, in such a manner that the column is supported above or over vault A, substantially as and for the purpose described.

CHARLES T. HARVEY.
